LOCKING DEVICE FOR ELECTRIC LIGHT BULBS

Herbert C. Healey, East Bridgewater, Mass.

Application June 1, 1936, Serial No. 82,733

8 Claims. (Cl. 173—356)

This invention relates to a device for preventing the unauthorized removal of electric light bulbs from sockets in which they are inserted.

It is an object of the invention to provide a device such that the socket element, into which the lamp base is screwed, will normally turn freely with the bulb so as to prevent the unscrewing of the light bulb therefrom. According to the invention, a clutch device is provided by which the socket element can be temporarily held against rotation for the insertion or removal of an electric light bulb, a special kind of electromagnet being required for the operation of such clutch device.

For a more complete understanding of the invention, reference may be had to the disclosure of certain embodiments thereof in the following description and on the drawing of which—

Figure 1 is a perspective view of the several parts of a device embodying the invention.

Figure 2 is a longitudinal sectional view of the same.

Figure 3 is a sectional view of a portion of the device shown in Figure 2, the parts being shown in a different position of operation.

Figure 4 is a section on the line 4—4 of Figure 2.

Figure 5 is a section on the line 5—5 of Figure 3.

Figure 6 is a fragmentary sectional view showing a modified detail.

Figure 7 is a sectional view of a modified form of the invention.

The invention may be embodied in an adapter capable of being inserted in an ordinary outlet adapted to receive an electric light bulb, as illustrated in Figure 2, or may be embodied in a fixture, an example of which is illustrated in Figure 7. In either case, the invention includes a support to which an electric light socket is permanently but rotatably attached, and clutch means by which the socket can be temporarily locked against rotation relative to its support. In Figure 2 is illustrated an adapter consisting of a support in the form of a plug element 10 and a socket element 12 permanently attached thereto, the latter being adapted to receive the base of a conventional electric light bulb 14. The plug portion 10 is provided with a threaded shell 16 adapted to screw into a conventional socket 20 having a central contact member 22. The plug element 10 and the socket element 12 may be secured together for free relative rotation as by a central rod 24 which has a head 26 at one end and is peened at the other end as at 28 over

a washer 30 which bears on an insulating disk 31. The rod 24 extends through a tube or jacket 32 of insulating material and is preferably freely rotatable therein. Between the plug element 10 and the socket element 12 is a clutch device 5 comprising two metal blocks 34 and 36 which have square transverse cross sections of the same size. Each of these blocks is provided with a central bore 40 through which pass the rod 24 and the insulating tube 32. Surrounding the tube 32 within the bores 40 is a spring 42, one end of which presses against a metal plate 44 mounted on one end of the plug element 10, the other end of the spring 42 bearing against a metal plate 46 which is secured to the base of the socket shell 12. The plate 44 is electrically connected as by a wire 48 to the shell 16 of the plug element 10, the connection between the wire 48 and the shell 16 being made by a metal element such as a drop of solder 50 which projects radially beyond the shell 16, so that, when the adapter is screwed into the socket 20, the projecting portion of the element 50 comes into binding engagement with the edge of the shell in the socket 20 so that the plug element 10 is thus frictionally held against rotation which might tend to unscrew it from the socket 20, this frictional binding engagement occurring before the plug element 10 has penetrated the socket far enough to press the resilient contact element 22 in against the bottom of the socket. This leaves the head 26 of the rod 24 in sufficient contact with the element 22 for good transmission of current but leaves the rod 24 to turn freely without binding engagement against the element 22.

The plates 44 and 46 are centrally depressed as at 52 to receive the remote end faces of the blocks 34 and 36. Thus the block 34 is held against rotation relative to the plug element 10 40 while the block 36 is held against rotation relative to the socket element 12. As long as these two blocks are relatively rotatable with respect to each other, the socket element 12 can be freely rotated relative to the plug element 10. This is 45 the normal condition of the adapter, as illustrated in Figure 2. Thus, if a bulb 14 is engaged in the socket 12, any effort to rotate the bulb 14 will result in rotation of the socket element 12 and the block 36. In order to hold the socket element 12 against rotation for the removal or insertion of a bulb, the blocks 34 and 36 may be temporarily held together by means of a clutch element 56 which, as shown in Figure 1, may consist of a disk having a square central aperture 55

58 adapted to receive the block 34 or 36, and a pair of parallel ears 60 at opposite sides of the aperture 58, these ears being adapted to fit against opposite side faces of the block 36 as indicated in Figure 2. The clutch member 56 is 5 normally held in the position shown in Figure 2 by a light compression spring 62, one end of which is preferably secured to the member 56. If preferred, suitable tension springs 63 may be 10 employed as illustrated in Figure 6. Whenever the clutch member 56 is moved toward the left so that the ears 60 simultaneously engage portions of the blocks 34 and 36, the blocks are held 15 against relative rotation. Since the plug element 10 is normally bound frictionally within the socket 20, the socket 12 is thus held against rotation permitting the insertion or removal of an electric light bulb 14. If desired, the distance 20 of movement of the clutch member 56 toward the left may be limited by the provision of a pair of stops 64 to make difficult the operation of the device otherwise than by the use of a suitable magnet. A suitable tubular casing member 66 surrounds the adapter so as to prevent access 25 thereto. In order to shift the clutch member 56, it is preferably made of magnetic material, such as iron, so that, if the poles 70 of a strong magnet are suitably positioned at opposite sides of the casing 66, the magnetic flux will pull the 30 clutch member 56 to the left to the position shown in Figure 3. If at the time the magnet is put into operation, the blocks 34 and 36 are not registering, as illustrated in Figure 4, a slight rotation of the bulb 14 will bring the block 36 35 into registry with the block 34, whereupon the flux of the magnet will draw the clutch member 56 to the left so as to lock the blocks together. The casing 66 is preferably made of suitable non-magnetic material, such as copper or a moldable 40 plastic. This casing extends sufficiently beyond the end of the socket shell 12 to prevent movement thereof toward the right sufficient to expose the adapter. The casing is normally mounted on the end of the socket member 20, being 45 threaded thereon as at 72 on the threaded portion usually provided on a socket shell for the support of a shade or the like. The opposite end of the casing 66 may be threaded as at 74 for the support of a shade.

50 Figure 7 shows a clutch mechanism similar to that illustrated in Figure 2, but mounted in a structure which is a fixture rather than an adapter to be screwed into the conventional socket. As therein shown, the support to which 55 the socket is rotatably secured is a fixed base 80 of suitable insulating material, this base being secured to a wall 82 as by suitable screws 84. The plate 44 is mounted on the end of this base. A binding screw 86 is electrically connected to the 60 shell 12 by a wire 88 which leads from the plate 44, the latter being electrically connected to the shell 12 as hereinbefore described. The head 26 of the rod 24 is electrically connected to a binding post 90 by any suitable means such as a wire 65 or metal strip 92. A casing 94 is permanently secured by any suitable means to the base 80, this casing being of non-magnetic material.

70 It is evident that various modifications and changes may be made in the embodiments of the invention herein shown and described without departing from the spirit or scope of the invention as defined in the following claims.

I claim:-

75 1. A device of the class described, comprising a support, a socket for an electric light bulb ro-

tatably mounted on said support, clutch means operable by a magnet against a restoring force to hold said socket against rotation relative to said support, and a non-magnetic casing enclosing said clutch means.

2. A device of the class described, comprising a support, a socket for an electric light bulb rotatably mounted on said support, clutch means operable by a magnet against a restoring force to hold said socket against rotation relative to said support, and a non-magnetic casing surrounding said clutch means and socket to prevent access thereto when a light bulb is in place in the socket.

10 3. A device of the class described, comprising a socket adapted to receive the base of an electric light bulb, a support for said socket, means connecting said socket to said support and normally permitting free rotation of the socket relative to the support, clutch means magnetically operable to secure said socket and support temporarily against relative rotation and a non-magnetic casing enclosing said clutch means.

15 4. A device of the class described, comprising a support, a socket for an electric light bulb rotatably mounted on said support, and magnetically operable clutch means for holding said socket against rotation relative to said support, said clutch means including an element of magnetic material non-rotatable relatively to said socket but axially movable into locking engagement with said support, spring means normally holding said element out of engagement with said support, and a non-magnetic casing surrounding said clutch means and socket to prevent access thereto when a light bulb is in position in the socket.

20 5. A device of the class described, comprising a support, a socket for an electric light bulb mounted on said support and normally rotatable thereon, said socket including a threaded cylindrical shell adapted to receive the base of a light bulb and a central terminal normally engaged by the tip of the base of the light bulb, a pair of electric terminals on said support by which the device may be connected into an electric circuit, means holding said socket on said support and comprising a central rod extending from said central terminal in the socket to one of the terminals on the support and electrically connecting these terminals, means including a spring surrounding a portion of said rod electrically connecting said socket shell with the other terminal on said support, means insulating said rod from said spring and socket shell, clutch 25 means magnetically operable to hold said socket against rotation relative to said support, and a non-magnetic casing enclosing said clutch means.

30 6. A device of the class described, comprising a plug portion adapted to be screwed into a conventional socket for an electric light, a socket portion normally rotatable relatively to said plug portion, means connecting said plug and socket portions together, clutch means permanently and rotatably magnetically operable to hold said socket portion against rotation relative to said plug portion, and a non-magnetic casing surrounding said clutch means and socket portion to prevent access thereto.

35 7. A device of the class described, comprising a plug portion adapted to be screwed into a conventional socket for an electric light, a socket portion normally rotatable relatively to said plug portion, means permanently and rotatably connecting said plug and socket portions together,

clutch means magnetically operable to hold said socket portion against rotation relative to said plug portion, a lateral projection on said plug portion adapted to engage the edge of a socket into which the device is screwed to limit the penetration of said plug portion into the socket, and a non-magnetic casing enclosing said clutch means.

5. A device of the class described, comprising a plug portion adapted to be screwed into a conventional electric light socket, a socket portion rotatably connected to said plug portion, an axi-

ally movable clutch element of magnetic material normally rotatable with one said member relatively to the other said member, said clutch element having a portion adapted to engage said other member when said element is axially shifted from its normal inactive position whereby said members are temporarily locked together against relative rotation, and spring means yieldingly pressing said clutch element to its normal inactive position.
